BALLAST TAMPING APPARATUS

Royce Kershaw, Montgomery, Ala., assignor to Kershaw Manufacturing Company, Inc., a corporation of Alabama

Application May 31, 1955, Serial No. 511,835

2 Claims. (Cl. 104—12)

This invention relates to track raising and ballast tamping apparatus and has for an object the provision of such apparatus which shall be particularly adapted for supporting rail sections adjacent the point they are connected to each other and adjacent the centers thereof, together with improved means for tamping ballast adjacent the outside of the rails and around the ends of the cross ties while the rails are thus supported.

Another object of my invention is to provide ballast tamping apparatus in which the tamping action applied to the ballast by the tamping members is a combination of percussion and vibratory movements.

A further object of my invention is to provide apparatus of the character designated in which the actuating units for the ballast engaging members are mounted on pantograph frameworks whereby the units move in substantially vertical planes as they are raised and lowered.

A still further object of my invention is to provide apparatus of the character designated in which the means for lifting the rails is positioned outwardly of the ends of the cross ties.

Briefly, my improved track raising and ballast tamping apparatus comprises a vehicle having wheels adapted to run upon the rails of the track, together with jack mechanisms mounted on the vehicle and engageable with the road bed for raising the rails and cross ties attached thereto. Supporting frames are mounted at the sides of the vehicle and are adapted for vertical movement relative to the vehicle. Mounted for vertical reciprocating movement in the supporting frames are actuating units. Pivotedly connected to each of the supporting frames and operatively connected to the actuating units are ballast engaging members which are so constructed that upon reciprocation of the actuating units, the ballast engaging members contact the ballast with a percussive force. Also, improved means is provided for vibrating the ballast engaging members during the tamping operation.

Apparatus embodying the features of my invention is shown in the accompanying drawings forming a part of this application, in which:

Fig. 1 is a side elevational view, showing the rails and cross ties in raised position and the ballast engaging members in operative position;

Fig. 2 is a plan view, a portion of the jack mechanism being omitted for the sake of clarity;

Fig. 3 is a front elevational view showing the ballast engaging members in operative position and the jack mechanism in inoperative position;

Fig. 4 is an enlarged detail view, partly broken away and in section, showing the mechanism for actuating the ballast engaging members, together with the means for vibrating the same;

Fig. 5 is a sectional view taken generally along the line V—V of Fig. 4, the supporting frame for the actuating unit being omitted, for the sake of clarity;

Fig. 6 is a sectional view taken along the line VI—VI of Fig. 4;

2

Fig. 7 is a sectional view taken along the line VII—VII of Fig. 4;

Fig. 8 is an enlarged perspective view, partly broken away and in section, showing a lifting foot for the jack mechanism;

Fig. 9 is an enlarged elevational view showing the eccentric shaft employed to vibrate the ballast engaging members;

Fig. 10 is an end view of the shaft shown in Fig. 9, taken along the line X—X of Fig. 9; and,

Fig. 11 is a schematic diagram illustrating the hydraulic system employed.

Referring now to the drawings for a better understanding of my invention, I show a vehicle 10 adapted to run upon the rails 11 of a railroad track. The rails 11 are supported in the usual manner by cross ties 12. The vehicle frame comprises side channel members 13—13' and 14—14' connected at the forward end of the vehicle by transverse channels 16 and 17. The rear ends of the channels 13—13' and 14—14' are connected by transverse channels 18 and 19. As shown in Figs. 1 and 3 the channels 13—13', 14—14', 16—17 and channels 18—19 face each other to form box-channels at the sides and ends of the vehicle. Secured to the under surface of the side channels 13—13' and 14—14' are suitable bearing blocks 21 for receiving a forward axle 22 and the rear axle 23 upon which are mounted the usual wheels 24 for the vehicle.

Mounted at the forward end of the vehicle 10 is an internal combustion engine 26 having a rearwardly extending drive shaft 27 mounted for rotation in suitable bearings 28. Mounted on the drive shaft 27 are sprocket wheels 29 and 31. The sprocket wheel 29 is connected by means of a sprocket chain 32 to a sprocket wheel 33 mounted on a shaft 34. The shaft 34 drives fluid pressure pumps 36 and 37 which are mounted on a horizontal plate 38, as shown in Fig. 2. The sprocket wheel 31 is connected by a sprocket chain 39 to a sprocket wheel 41 mounted on a shaft 42. The shaft 42 drives fluid pressure pumps 43 and 44 which are mounted on a horizontal plate 46. Suitable openings 47 and 48 are provided in the plates 38 and 46 through which the sprocket chains 32 and 39 pass.

In order to lift the rails 11 and the cross ties secured thereto, I provide a lifting mechanism indicated generally at 49 which is positioned forwardly of the rear wheels of the vehicle, as shown in Fig. 1. Extending transversely of the side channels 13—13' and 14—14' are channels 51 and 52. Secured to the sides of the side channels 13 and 14 and projecting outwardly therefrom directly below the channels 51 and 52 are vertical plate members 53 and 54 having aligned vertically disposed slots 56. Passing through the slots 56 and movable vertically therein are pins 57 having rail clamping units 58 secured thereto. Connecting the channels 51 and 52 adjacent the centers thereof are plate members 59. Secured to the plates 59 and extending upwardly therefrom is a vertical post 61. Mounted for sliding movement on the post 61 is a sleeve member 62 which is pivotally connected to a movable frame 63 by means of a pin 60. Secured to the undersurface of the movable frame 63 and extending downwardly from each side thereof, are transverse plate members 64 and 66. Pivotally connected to the plates 64 and 66 by means of pins 67 are the upper ends of links 68. The lower ends of the links 68 are pivotally connected to the inner ends of the rail clamping units 58 by means of pivot pins 69. It will thus be seen that upon raising the movable frame 63 relative to the vehicle, the clamping units 58 move into engagement with the rails 11.

Mounted at the outer ends of the movable frame 63 are vertically disposed, double acting fluid pressure cyl-

inders 71 and 72 having downwardly extending piston rods 73 and 74, respectively. Secured to the lower ends of each of the piston rods 73 and 74 is a block member 76 having a rounded lower end 77, as shown in Fig. 8. The block member 76 fits within a rectangular member 78 and is pivotally connected thereto by means of a pivot pin 79. Pivotally connected to the rectangular member 78 at right angles to the pivot pin 79 are upstanding lugs 81 and 82 which are formed integrally with a base member 83. The lugs 81 and 82 are pivotally connected to the rectangular member 78 by means of suitable pins 84. It will thus be seen that a universal joint is provided between the base member 83 and the lower ends of the piston rods 73 and 74. Fluid under pressure is supplied to an upper end of the cylinders 71 and 72 by means of conduits 86 and 87, respectively. Fluid under pressure is supplied to the lower ends of the cylinders 71 and 72 by means of conduits 88 and 89, respectively.

Extending transversely across the internal combustion engine 26 are I-beams 91 and 92. Secured to opposite ends of the I-beam 91 by means of diagonal plates 93 are transverse I-beams 94 and 96. As shown in Figs. 1 and 3 the upper edge of the I-beams 94 and 96 lie adjacent the lower edges of the I-beam 91. In like manner, secured to opposite ends of the I-beam 92 by means of the diagonal plates 93 are I-beams 97 and 98.

Connecting the outer ends of the I-beams 94 and 97 are spaced plate members 99 and 101. In like manner, connecting the outer ends of the I-beams 96 and 98 are spaced plate members 102 and 103. Extending upwardly between the plate members 99 and 101 and pivotally connected thereto by means of a pivot pin 104 is the upper end of a piston rod 106 of a fluid pressure cylinder 107. Extending upwardly between the plates 102 and 103 and pivotally connected thereto by means of a pivot pin 108 is the upper end of a piston rod 109 of a fluid pressure cylinder 111. Each of the fluid pressure cylinders 107 and 111 are pivotally connected to pantograph frameworks indicated generally at 112 and positioned at opposite sides of the vehicle.

In view of the fact that the pantograph frameworks 112 and the tamping apparatus carried thereby are identical in construction, only a description of one is deemed necessary. The pantograph framework 112 comprises a pair of laterally spaced upper arms 113 and a pair of laterally spaced lower arms 114. The forward ends of the pairs of arms 113 and 114 are pivotally connected by means of pivot pins 116 and 117, respectively, to an upstanding supporting structure indicated generally at 118 mounted at the forward end of the vehicle frame. Suitable diagonal braces 119 connect the upper end of the supporting frame 118 to the I-beams 94 or 96, as the case may be. The fluid pressure cylinders 107 and 111 extend vertically between the arms 113 and are pivotally connected thereto by means of pivot pins 121 which are connected to brackets 122 in turn rigidly secured to the arms 113 by any suitable means, such as by welding.

Pivotally connected to the rear ends of the arms 113 and 114 by means of pivot pins 123 and 124, respectively, is a vertically movable supporting frame 126 for an actuating unit 127. The supporting frame 126 is substantially rectangular, having upper side members 128 and lower side members 129. The forward ends of the upper side member 128 are connected by a transverse member 131 and the rear ends thereof are connected by a transverse member 132. In like manner, the forward ends of the lower side members 129 are connected by a transverse member 133 and the rear ends of the lower side members 129 are connected by a transverse member 134.

Secured to the forward end of the supporting frame 126 are upper and lower brackets 136 and 137, respectively. Connecting the brackets 136 and 137 and secured rigidly thereto are vertical members 138, which

are preferably cylindrical, as shown in Fig. 4. Projecting outwardly from the rear end of the supporting frame 126 are upper and lower brackets 139 and 141, respectively. The brackets 139 and 141 are connected by a vertical member 142 which is also preferably cylindrical in shape.

The actuating member 127 is also rectangular in shape and moves vertically within the supporting frame 126. The actuating unit comprises upper and lower side channel members 143 and 144, respectively, connected by a front wall 146, a rear wall 147 and vertical channel members 145 at the corners thereof. Secured to the forward wall 146 by means of bolts 148 is a sleeve member 149 which slidably engages the cylindrical member 138. In like manner, secured to the rear wall 147 by means of bolts 151 is a sleeve member 152 which slidably engages the vertical member 142.

Connecting the central portions of the upper side members 128 of the supporting frame 126 are spaced members 153 and 154. Pivotally connected to the members 153 and 154 by means of a pivot pin 156 is the upper end of a fluid pressure cylinder 157 having a downwardly extending piston rod 158. Extending transversely of the lower side members 144 of the actuating unit 127 are spaced members 159 and 161 to which the lower end of the piston rod 158 is connected by means of a pivot pin 162. Communicating with the upper end of the fluid pressure cylinder 157 is a conduit 163 and communicating with the lower end thereof is a conduit 164. It will thus be seen that by alternately introducing the fluid under pressure through the conduits 163 and 164 that reciprocatory motion is applied to the actuating unit 127.

Connecting the upper and lower side members 143 and 144 adjacent the forward side of the actuating unit 127 are vertical plates 166 and 167 and connecting the side plates 143 and 144 adjacent the rear end of the actuating unit are vertical plates 168 and 169. Mounted for rotation between the vertical plates 166 and 167 is a shaft 171 and mounted for rotation between the vertical plates 168 and 169 is a shaft 172. As shown in Fig. 9, the shafts 171 and 172 are provided with an enlarged eccentric portion 173. Surrounding the enlarged eccentric portions 173 of the shafts 171 and 172 are the upper ends of connecting rods or links 174 and 176, respectively. The lower ends of the connecting rods 174 and 176 are pivotally connected by means of pivot pins 177 and 178 to ballast engaging members or tamping tools 189 and 191, respectively, which are arranged on opposite sides of the crosstie. As shown in Figs. 1 and 4, the tamping tools 189 and 191 are pivotally connected, by means of a pin 192 to a supporting bracket 193 mounted at the lower end of the supporting frame 126. Tamping tools 189 and 191 comprise upper portions extending outwardly from pin 192 in a direction generally parallel to the rails and lower portions extending downwardly from the upper portions and curved inwardly whereby the tools are adapted to tamp ballast beneath a cross tie, as shown in Fig. 1. Mounted on the shafts 171 and 172 are sprocket wheels 194 and 196 respectively, which are connected by a sprocket chain 197. Mounted on the shaft 171 inwardly of the sprocket 194 is a second sprocket 198 which is connected to a drive sprocket 199 by means of a sprocket chain 201. The sprocket 199 is mounted on a drive shaft 202 of a fluid pressure motor 203.

Mounted on the front axle 22 of the vehicle is a sprocket wheel 204 which is connected by a sprocket chain 206 to a sprocket wheel 207 of a transmission unit 208. Connected to the transmission unit 208 by a suitable sprocket and chain connection 209 is a fluid pressure motor 211. The fluid pressure motor 211 is preferably of the reversible type whereby the direction of travel of the vehicle along the rails 11 can be changed by merely reversing the direction of flow of the fluid

through the motor 211. The transmission unit is provided with a suitable operating handle 210.

Mounted adjacent the rear end of the vehicle 10 is a supply tank 212 for supplying fluid to the pumps 36, 37, 43 and 44. As shown in Fig. 11, fluid for the hydraulic cylinder 71 of the jack mechanism is supplied by the pump 36 through a control valve 213. Fluid for the hydraulic cylinder 72 of the jack mechanism is supplied by the pump 37 through a control valve 214. Fluid for the hydraulic cylinders 107 and 111 of the pantograph frames is supplied by the pumps 36 and 37 through control valves 216 and 217, respectively.

Fluid for the hydraulic cylinders 157 of the actuating units 127 is supplied by the pumps 36 and 37 through control valves 218 and 218a. Fluid for the fluid pressure motors 203 is supplied by the pumps 43 and 44 through control valves 219 and 219a. Fluid for the motor 211 is supplied by the pump 44 through a control valve 220.

From the foregoing description, the operation of my improved apparatus will be readily understood. The vehicle 10 is moved along the rails 11 until the actuating unit 127 is positioned over the cross tie under which ballast is to be tamped. My apparatus is particularly adapted for tamping ballast beneath cross ties adjacent the joints of the rails and adjacent the mid point of the rail sections, whereby the rails may be leveled by raising either rail the proper distance and then tamping ballast beneath the cross tie adjacent which the actuating unit 127 has been positioned to tamp. The rails are thus maintained in the leveled position until ballast has been tamped beneath the remaining cross ties. With the vehicle thus positioned, fluid is introduced to the upper ends of the hydraulic cylinder 71 and 72 by means of the control valves 213 and 214. The base members 83 of the lifting feet are then moved into contact with the road bed whereupon the movable frame 63 is raised relative to the vehicle. As the movable frame 63 moves upwardly, the links 68 move the clamping units 58 into contact with the rails 11. Continued upward movement of the movable frame 63 lifts the rails together with the cross ties secured thereto.

After the rails have been adjusted to the proper elevation by actuating the hydraulic cylinder 71 and 72 either individually or together, the frame 126 is moved to lowered position, as shown in Fig. 1. Frame 126 is lowered by introducing fluid under pressure at the upper ends of the cylinders 107 and 111 by actuating the control valves 216 and 217, respectively.

With the frame 126 and ballast tamping members 189 and 191 in the position shown in Fig. 1, the control valves 218 and 218a are actuated, individually or together, thereby introducing fluid under pressure alternately through the lines 163 and 164 to the hydraulic cylinder 157, thus reciprocating the piston rod 158 and the actuating frame 127 within the supporting frame 126. As the actuating frame 127 is reciprocated, the connecting rods 174 and 176 cause reciprocatory movement of the ballast tamping members, thereby applying a percussive force to the ballast. Also, as the ballast tamping members are reciprocated, fluid is introduced to the fluid pressure motors 203 individually or together, thus rotating the shafts 171 and 172, whereupon vibratory motion is applied to the ballast tamping members through the connecting rods 174 and 176. With the valve 218 or 218a moved to introduce fluid under pressure to the cylinder 157 and the valve 219 or 219a moved to introduce fluid under pressure to motor 203, both percussive and vibratory forces are applied to the ballast through the ballast tamping members.

After the ballast has been tamped beneath the cross tie, the supporting frame 126 is raised by lifting the pantograph frames 112. The lifting feet of the jack mechanism are then raised by introducing fluid under pressure at the lower ends of the hydraulic cylinders 71 and 72.

Upon raising the lifting feet, the movable frame 63 and the links 68 move downwardly thus disengaging the clamping units 58 from the rails 11. The vehicle is then propelled along the tracks to the next tamping position by moving the control valve 220 to the proper position, depending upon whether it is desired to move forward or in reverse. Upon actuation of the control valve 220, the motor 211 drives the axle 22 through the transmission unit 208 and the sprocket connection thereto.

In view of the foregoing, it will be seen that I have devised an improved apparatus for raising the rails of a railroad track and then tamping ballast beneath the cross ties at selected positions whereby the rails are maintained in proper position until the ballast has been tamped beneath the remaining cross ties. In actual practice I have found that my improved apparatus is satisfactory in every respect and that the individual rails of the track can be positioned at the correct elevation in a minimum of time and with the expenditure of a minimum of labor.

While I have shown my invention in but one form, it will be obvious to those skilled in the art that it is not so limited but is susceptible of various changes and modifications without departing from the spirit thereof, and I desire, therefore, that only such limitations shall be placed thereupon as are specifically set forth in the appended claims.

What I claim is:

1. In apparatus for tamping ballast under a railroad crosstie, a vehicle embodying a main frame and having wheels adapted to run upon the rails of a track, a vertically movable supporting frame mounted on said main frame, a pair of oppositely directed ballast engaging tamping tools pivotally mounted on the lower portion of said supporting frame on a generally horizontal axis extending transversely of the rails, said axis in the working position of the tools being positioned generally over the center of a crosstie whereby the tools engage ballast on opposite sides of the crosstie, each of said tamping tools having an upper portion extending outwardly from the axis in a direction generally parallel to the rails and a lower portion fixed to and extending downwardly from said upper portion adapted to reach under the crosstie for engaging ballast in tamping relation, a pair of links pivotally connected adjacent their lower ends to the upper portions of the tamping tools, one of said links being connected to one tamping tool at a position laterally spaced from said axis and the other link being connected to the other tamping tool at a position laterally spaced from said axis, reciprocable fluid pressure means operatively connected to the adjacent upper ends of the links simultaneously to move the links vertically and simultaneously to pivot the tamping tools about said axis through said links in strokes of substantially equal intensity and magnitude while said axis is held in a vertically fixed position, and vibratory means operatively connected to the tamping tools to impart a vibratory motion to said tamping tools, said tamping tools being simultaneously vibrated and pivoted about their vertically fixed axis upon reciprocation of said fluid pressure means and actuation of said vibratory means.

2. In apparatus for tamping ballast under a railroad crosstie, a vehicle embodying a main frame and having wheels adapted to run upon the rails of a track, a vertically movable supporting frame mounted on said main frame, a pair of oppositely directed ballast engaging tamping tools pivotally mounted on said supporting frame on a common generally horizontal axis extending transversely of the rails, said common axis being positioned generally over the center of a crosstie in working position whereby the tools engage ballast on opposite sides of the crosstie, each of said tamping tools having an upper portion extending outwardly from the common axis in a direction generally parallel to the rails and a lower portion fixed to and extending downwardly from said upper portion to reach under the crosstie for engaging ballast in tamping

relation, connecting means on said supporting frame operatively connected to the upper portions of said tamping tools at positions laterally spaced from the common axis, reciprocating fluid pressure means operatively connected to said connecting means simultaneously for pivoting said tamping tools about the common axis in strokes of substantially equal magnitude while the axis is held in a vertically fixed position, and vibratory means operatively connected to the tamping tools to impart a vibratory motion to said tamping tools, said tamping tools being simultaneously vibrated and pivoted about their vertically fixed axis upon reciprocation of said fluid pressure means and actuation of said vibratory means.
